Application March 9, 1936, Serial No. 67,808
In Germany March 12, 1935

5 Claims. (Cl. 179—122)

This invention relates to a new and novel type of microphone.

- Microphones are known comprising fixed electrodes and loose granulated carbon and in which the fixed electrodes are so arranged in deep cavities that the free outer surfaces thereof are completely covered with the contact powder. The electrodes are arranged lateral to the path of granules and extend at right angles to said path.
- 10 It happens hereby that the current threads coming from the limiting surfaces of the path of granules impinge only on a definite comparatively small region of the electrodes. This condition entails a high current density at the electrodes.
- 15 Owing to this high current density there occurs through the electrode a large drop of the direct voltage; this part of the direct potential being not sufficiently controlled by the movement of the diaphragm, and consequently it remains substantially without influence upon the delivered alternating voltage. This high current density however causes a strong noise potential of the microphone.

The present invention relates to a microphone of the type above described and aims at overcoming the said drawbacks. This is accomplished in accordance with the invention in that provision is made so that the current threads starting from the path of carbon granules have, up to 25 all places of the electrodes, the same length or at least approximately the same length. In addition the effective faces of the electrodes are substantially larger than the actual cross section of the granulated carbon which likewise insures a 30 current density as low as possible.

In the drawing two embodiments of the invention are represented by way of example.

Figure 1 shows the cross section of a rectangular microphone.

40 Figure 2 represents a top view of this microphone.

Figure 3 shows the cross section of a round microphone.

Figure 4 shows the top view of this microphone.

45 In Figures 1 and 2, the electrodes 1 and 2 are arranged substantially laterally to the granulated path in cavities 3 and 4 of the casing 5 and this in such manner that the current threads 6 between the faces of electrodes 1 and 2 have approximately the same length from the path of the carbon granules. This is accomplished by having the outer surfaces of the electrodes 1 and 2 arranged in a steep angle relative to the limiting edges of the path of granules. The microphone 50 casing 5 is entirely filled with carbon granules,

the casing being completed by a diaphragm 7, a cover plate 8 and spacer rings 9, 10, 11, and 12. The microphone casing may be constructed of metal in order that the heat delivery be as favorable as possible. In this case the inside must of course be covered with a non-conducting lacquer to provide insulation for the carbon granules and also electrodes 1 and 2. Obviously, also other material of favorable heat conduction such as ceramic material may be utilized without departing from the spirit of the invention.

As compared with the rectangular shape of the microphone according to Figures 1 and 2, the microphone according to Figures 3 and 4 has the further advantage that it can be used in any 15 position. The rectangular microphone however must be suspended always in such a position that the electrodes are vertical.

In Figures 3 and 4, the electrodes are designated by 13 and 14. The electrode 13 has an annular shape and is mounted in a cavity 20. The electrode 14 forms a central cylindrical body which has on one end face a circular recess or depression of semi-circular cross section. This recess or depression is arranged in the manner 25 that it extends about the limiting or boundary edges 15 of the path of granulated carbon.

Item 16 designates the microphone casing, item 17 is the diaphragm, and 18 designates a cover plate. As seen in Figure 3 the current lines 19 extend over the same distance from the limiting edge 15 of the path of granules to all places of electrode 14. The same is also the case for electrode 13. In order to prevent the granules sticking together and forming a mass, the microphone 30 casing may be provided with an intermediate 35 layer consisting of gauze or similar material such as is shown by item 21 in Figures 1 and 2. The object of gauze 21 is to maintain and insure uniform distribution of the carbon granules along 40 the diaphragm 7 in Fig. 1 and diaphragm 17 in Fig. 3. For example, when the microphone happens to be in a vertical position, the carbon particles will not pack together with the result that the operation of the microphone will be independent of the position of the instrument. In fact, the constituent members of the texture of the gauze act as a plurality of containers or pockets 45 for the carbon granules.

We claim:

1. A carbon microphone having carbon granules in contact with a diaphragm and electrodes arranged so that the current lines in the direction of said diaphragm through the path of the carbon granules between the faces of the elec-

50

55

trodes are substantially the same length, comprising a diaphragm, a circular casing, a depending cavity located at the outer rim of said casing, a second depending cavity located at the central portion of said casing, carbon granules filling both depending cavities and the space within said casing, a ring-like electrode located within the rim of said casing, a second electrode located within said second cavity, the face of at least one of said electrodes presenting an angle which is steep with respect to the plane of the diaphragm and said casing, said diaphragm arranged for enclosing said casing and serving to retain said carbon granules in position, the effective surface of said electrodes being substantially larger than the cross-section of the carbon granules.

2. A carbon microphone having carbon granules in contact with a diaphragm and electrodes arranged so that the current lines in the direction of said diaphragm through the path of the carbon granules between the faces of the electrodes are substantially the same length, comprising a diaphragm, a circular casing, a depending cavity located at the outer rim of said casing, a second depending cavity located at the central portion of said casing, carbon granules filling both depending cavities and the space within said casing, a ring-like electrode located within the rim of said casing, a second electrode having a cross-sectional area in the form of a semi-circular cavity located within said second cavity, the face of at least one electrode presenting an angle which is steep with respect to the plane of the diaphragm and said casing, said diaphragm arranged for enclosing said casing and serving to retain said carbon granules in position, the effective surface of said electrodes being substantially larger than the cross-section of the carbon granules.

3. A carbon microphone having carbon granules in contact with a diaphragm and electrodes arranged so that the current lines in the direction of said diaphragm through the path of the carbon granules between the faces of the electrodes are substantially the same length, comprising a diaphragm, a circular casing, a depending cavity located at the outer rim of said casing, a second depending cavity located at the central portion of said casing, carbon granules filling both depending cavities and the space within said casing, a ring-like electrode located within the rim of said casing, a second electrode located within said second cavity, the face of at least one electrode presenting an angle which is steep with respect to the plane of the diaphragm and said casing, said diaphragm arranged for enclosing

said casing and serving to retain said carbon granules in position, the effective surface of said electrodes being substantially larger than the cross-section of the carbon granules, and a gauze-like member interposed between said casing and said diaphragm to prevent said carbon granules sticking together.

4. A carbon microphone having carbon granules in contact with a diaphragm and electrodes arranged so that the current lines in the direction of said diaphragm through the path of the carbon granules between the faces of the electrodes are substantially the same length, comprising a diaphragm, a circular casing, a depending cavity located at the outer rim of said casing, a second depending cavity located at the central portion of said casing, carbon granules filling both depending cavities and the space within said casing, a ring-like electrode located within the rim of said casing, a second electrode located within said second cavity, the face of at least one electrode presenting an angle which is steep with respect to the plane of the diaphragm and said casing, said diaphragm arranged for enclosing said casing and serving to retain said carbon granules in position, the effective surface of said electrodes being substantially larger than the cross-section of the carbon granules, a gauze-like member interposed between said casing and said diaphragm to prevent said carbon granules sticking together, and a cover plate extending over the front of said diaphragm.

5. A carbon microphone having carbon granules in contact with a diaphragm and electrodes arranged so that the current lines in the direction of said diaphragm through the path of the carbon granules between the faces of the electrodes are substantially the same length, comprising a diaphragm, a circular casing, a depending cavity located at the outer rim of said casing, a second depending cavity located at the central portion of said casing, carbon granules filling both depending cavities and the space within said casing, a ring-like electrode located within the rim of said casing, a second electrode located within said second cavity, the face of said ring-like electrode presenting an angle which is steep with respect to the plane of the diaphragm and said casing, the face of said second electrode having a recess of semi-circular cross-section, said diaphragm arranged for enclosing said casing and serving to retain said carbon granules in position, the effective surface of said electrodes being substantially larger than the cross-section of the carbon granules.
